(57) **CLAIM**

The ornamental design for a hose storage apparatus, as shown and described.

DESCRIPTION

FIG. 1 is an isometric view of a hose storage apparatus according to the present invention.

FIG. 2 is a right side elevation view of the hose storage apparatus of FIG. 1.

FIG. 3 is a left side elevation view of the hose storage apparatus of FIG. 1.

FIG. 4 is a front elevation view of the hose storage apparatus of FIG. 1.

FIG. 5 is a rear elevation view of the hose storage apparatus of FIG. 1.

FIG. 6 is a top plan view of the hose storage apparatus of FIG. 1; and,

FIG. 7 is a bottom plan view of the hose storage apparatus of FIG. 1.

1 Claim, 7 Drawing Sheets

FIG. 1

FIG. 2

FIG. 3

FIG. 4

FIG. 5

FIG. 6
